UNITED STATES PATENT OFFICE

119,613

DESIGN FOR A DRAINBOARD

Nicholas L. Etten, Waterloo, Iowa

Application July 4, 1939, Serial No. 85,844

Term of patent 14 years

To all whom it may concern:

Be it known that I, Nicholas L. Etten, a citizen of the United States and a resident of Waterloo, in the county of Blackhawk and State of Iowa, have invented a new, original, and ornamental Design for a Drainboard, of which the following is a specification, reference being had to the accompanying drawing, forming part thereof.

Fig. 1 is a perspective view of a drainboard showing my new design;

Fig. 2 is a front elevational view; and
Fig. 3 is an end elevational view thereof;

I claim:

The ornamental design for a drainboard, substantially as shown.

NICHOLAS L. ETSEN.
